Primary Examiner — Lilyana Bekic(74) *Attorney, Agent, or Firm* — Knobbe, Martens, Olson & Bear LLP(57) **CLAIM**

The ornamental design for a breathing assistance apparatus, as shown and described.

DESCRIPTION

FIG. 1 is a front, top, right side perspective view of a breathing assistance apparatus showing our new design; FIG. 2 is a front, bottom, left side perspective view thereof; FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines illustrate portions of the breathing assistance apparatus that form no part of the claimed design.
